UNITED STATES PATENT OFFICE

ROY W. BROWN, OF AKRON, OHIO, ASSIGNOR TO THE FIRESTONE TIRE AND RUBBER COMPANY, OF AKRON, OHIO, A CORPORATION OF OHIO

METHOD AND APPARATUS FOR USE IN MANUFACTURE OF RUBBERIZED FABRICS

Application filed June 8, 1922. Serial No. 566,892.

This invention relates, in a general way, to the manufacture of rubberized fabric, particularly to fabric designed and intended to be used in the manufacture of articles of rubber and fabric, such as automobile tires, or the like, in which the fabric is prepared by being passed through a bath of rubber in solution.

The usual solvent for rubber employed is benzol, which, because of its highly inflammable character, requires specially constructed apparatus for the drying of the fabric and recovery of the benzol. In the form of apparatus to which this invention relates, 15 the fabric is led through a bath of rubber in solution and then into a large enclosed chamber which is heated so that the benzol will evaporate quickly. In order to prevent explosions occurring in the interior of the drying chamber, the atmosphere therein usually contains an inert gas, such as carbon dioxide or producer gas, in such proportion as to constitute a non-inflammable mixture with the benzol. It is essential that the percentage of producer gas relative to the benzol be maintained at a definite amount in order to make the operation of the apparatus safe and practicable, and as the apparatus is necessarily closed during operation, it is essential 25 that some means be provided for readily determining the character of the gaseous contents of the drying chamber.

The purpose of this invention is to devise a simple and efficient device for indicating 35 the relative percentage of benzol and producer gas in the drying chamber and to so construct the various parts of the apparatus that the readings obtained thereby will be accurate.

For this purpose there is combined with the 40 drying chamber a device by which the contents of the chamber may be determined at all times, and by which, should the percentage of benzol be increased, it will be 45 immediately indicated. In this manner the

operation of the drying apparatus will be safe at all times.

In the drawings accompanying the application is shown one form of the device in combination with any suitable drying apparatus, it being understood that, having explained 50 the principles of the invention, changes and modifications may be made without sacrificing the essentials of the invention.

In the drawings: 55
Figure 1 is a view showing, diagrammatically, the arrangement of the various elements which constitute the apparatus of the invention;

Figure 2 is a cross section through one 60 form of resistance member which constitutes one element of the invention; and

Figure 3 is a plan view of the resistance coil.

There is here shown at 1, a form of drying 65 chamber and while any suitable type of enclosed chamber may be used, the one illustrated has been in successful operation and may be described briefly. The fabric is indicated by the numeral 2 passing from a supply roll 3 into a tank 4 in which is located the bath of rubber dissolved in benzol, or other solvent.

The fabric passes into the rubber solution 75 and then through a passageway 5, the walls of which dip into the rubber solution. In the passage 5 are located squeeze rolls 6 which force the rubber into the fabric and expel an excess of the solution. The fabric then enters the enclosed drying chamber 1 through a gateway 7 and while in the chamber is looped back and forth over idler rolls 8 and past a plurality of heaters 9 until it is dried sufficiently to be conducted from the chamber through a gateway 10 and is rolled up at 11.

The inert gas with which the chamber is filled is conducted into the chamber through an inlet pipe 12, and the chamber is emptied through a pipe 13 at the bottom of the 80 85 90

chamber by which the inert gas and fumes of benzol or other solvent are led to any suitable reclaiming apparatus where the solvent is recovered for reuse.

- 5 In order to determine and indicate the percentage of benzol in the mixture taken from the drying apparatus, if benzol is used, so that the contents of the chamber may be maintained at a safe and workable stage, 70
10 I make use of certain well known properties 75 of gas by which they affect the electric resistance of conductors surrounded by the gas.

From the producer gas line 12, there is 15 provided a branch pipe 14 and from the drying chamber outlet pipe a branch pipe 15, each pipe being of substantially the same size. The gas from each line is then led to a filter 16 and through a narrow orifice 20 plate 17 so that both the producer gas and the chamber gas, as the gas from the drying apparatus may be called, are freed from any foreign substance and given a constant velocity with low pressure. From the orifice 25 plate 17, the producer gas is conducted by a pipe 18 to and discharged within a chamber or box 19 which contains a coil of resistance wire. The chamber gas is led from plate 17 by pipe 20 to a second chamber or box 21 30 which also contains a resistance coil.

One of these chambers or boxes is illustrated in Figures 2 and 3, in which the box is composed of two recessed plates 22 between which is held a disk of suitable non-conducting substance, preferably a sheet of mica 23, in the center of which is located an aperture 24. The resistance coil is indicated by the numeral 25 and is passed back and forth across the aperture. The gas enters 35 the chamber on one side of the plate 23 and leaves at the other side so that it must pass across the coil.

The producer gas and the chamber gas pass out of the resistance coil enclosure by 40 pipes 26 and discharge below the surface of water contained in a jar 27. By-passes 45 having control valves 29 may also lead from the pipes 18 and 20 to the water jar 27 so that the amount of gas passing over 50 the coils 25 may be regulated.

The water in the jar is supplied by a pipe 30 and kept at a constant level by overflow pipe 31, having a trap 32 therein. An outlet pipe 33 serves to withdraw the mixture 55 of gases from the top of the water jar.

The coils 25 are located on either side of a Wheatstone bridge 34, the galvanometer of which is indicated by numeral 35. The Wheatstone bridge, containing the coils 25, 60 is so arranged and adjusted that when the percentage of benzol in the chamber 1 is at a safe and workable point, the current flowing on both sides of the bridge will be the same and the galvanometer will not register. 65 Should the percentage of benzol increase,

the gas flowing around the right coil 25 will change in character and the resistance of the right-hand coil will vary, due to the change in thermal conductivity of the gas, and the change will be registered on the galvanometer. It is desirable that the current through the coils on both sides of the Wheatstone bridge maintain their temperature somewhat higher than the temperature of the gases which pass around them, so as to obtain correct readings from the installation. 75

In order to obtain the accurate results desired, the gases flowing over both coils 24 should be freed from foreign substance, which is assured by the gas filters, and the velocity should be constant while the volume is low as will be assured by the orifice plates and the by-pass 28 and also by the water jar through which the gases are exhausted under the same conditions. Also, to obtain the best results, the temperature of both coils should be constant and should be relatively high, this being assured by the heating coils 36 surrounding each resistance box 22. 80

The particular form of apparatus shown 85 is such as has been found to operate satisfactorily and to give excellent results in determining the benzol content of the drying chamber, and while the description has been precise and detailed to enable one skilled in 90 the art to practice the invention, it will be understood that changes and modifications may be made without varying the invention as comprised within the scope of the appended claims. 95

What I claim is:

1. An apparatus for the uses and purposes set forth comprising, the combination of an enclosed drying chamber adapted for the drying of material dissolved in a volatile solvent, means for admitting gas to one side of the chamber and exhausting the gas from the other side of said chamber, of a device arranged to be effected by the incoming and outgoing gases for comparing the relative 100 character of the said gases to determine the content of volatilized solvent in the outgoing gases. 105

2. An apparatus for the uses and purposes set forth comprising, the combination of an enclosed chamber adapted for the drying of material dissolved in a volatile solvent, means for withdrawing the solvent from the chamber, a resistance coil, and means for conducting a portion of the gases from the chamber 110 and passing it over said coil. 115

3. An apparatus for the uses and purposes set forth comprising, an enclosed drying chamber, means for drying material containing a volatile solvent in the chamber, means for withdrawing gas from the chamber, a resistance coil, means adapted to conduct a portion of the withdrawn gas around the resistance coil, and means for measuring the resistance of said coil. 120 125

4. An apparatus for the uses and purposes set forth comprising, an enclosed chamber, means for drying material containing a volatile solvent in said chamber, means for supplying said chamber with an inert gas, means for withdrawing the gas from the chamber, two resistance coils, means for comparing the resistance of said coils, means for passing a portion of said inert gas over one of said coils, and means for passing a portion of said chamber gas over the other coil. 70
5. An apparatus for the uses and purposes set forth comprising, an enclosed chamber, means for drying material containing a volatile solvent in the chamber, means for conducting a gas to the chamber, means for withdrawing the gaseous content from said chamber, by-passes from said conducting means and said withdrawing means, resistance members in said by-passes, and a device for measuring the relative resistance of said members. 80
- 15 6. An apparatus for determining the solvent content of a drying chamber comprising, an enclosed chamber, means for admitting an inert gas to one side of said chamber, means for withdrawing solvent carrying gas from the other side of said chamber, a branch pipe for said inert gas, a second branch pipe for 90
- 20 the chamber gas, means for controlling the velocity of gases in said pipes, a resistance coil in each branch pipe, and an electrical resistance measuring device connected to said coils. 95
- 30 7. An apparatus for determining the solvent content of a drying chamber comprising, an enclosed chamber, means for admitting an inert gas to one side of said chamber, means for withdrawing solvent carrying gas 100
- 35 from the other side of said chamber, a branch pipe for said inert gas, a second branch pipe for the chamber gas, means for controlling the velocity of gases in said pipes, a resistance coil in each branch pipe, an electrical resistance measuring device connected to said coils, and means for controlling the temperature of the gases surrounding the resistance coils. 105
- 40 8. Apparatus of the class described, comprising a plurality of fluid conducting systems, each having a discharge outlet, said outlets being on a common level, and a device common to said systems for maintaining a constant head of a liquid above said outlets 110
- 45 and substantially enclosing said liquid. 115
- 50 9. A method adapted for use in the manufacture of rubberized fabric or the like, in which the material is impregnated with a rubber solution and is treated in a drying chamber, said method comprising determining the character or composition of the gaseous content of said chamber by submitting said gaseous content to a device responding to changes in the thermal conductivity of the 120
- 55 gaseous content, comparing the variation in 125
- 60 65 130
- the resistance of said device due to changes in the thermal conductivity with the variation in the resistance of a similar device due to the thermal conductivity of an inert gaseous ingredient, and discharging the gaseous fluids under comparison against a constant head of liquid to cause said gaseous fluids to flow at equal velocities through both devices during the determination of the character or composition of the gaseous content of the drying chamber. 75
